UNITED STATES PATENT OFFICE.

ALBERT W. GRUNWALDT, OF ABRAMS, WISCONSIN.

DESIGN FOR A SECRETARY.

SPECIFICATION forming part of Design No. 28,668, dated May 17, 1898.

Application filed April 12, 1898. Serial No. 677,376. Term of patent 7 years.

To all whom it may concern:

Be it known that I, ALBERT W. GRUNWALDT, a citizen of the United States, residing at Abrams, in the county of Oconto and State of Wisconsin, have invented and produced a new and original Design for a Secretary, of which the following is a specification, reference being had to the accompanying drawings, forming part thereof.

- o In the drawings, Figure 1 is a front view of the secretary. Fig. 2 is a side view of the same.
- 5 The leading features of the design consist in the rectangular outlines formed of horizontal and vertical lines at the lower part of the secretary, the rectangular outlines arranged in an upwardly and rearwardly inclined plane at the middle part of the secretary, the vertical pillars and horizontal outlines at the front and upper part of the secretary, and the radiating fan-shaped ornamentation at the middle of the upper part of the secretary, behind the plane of the said pillars, and on its sides.
- 5 The rectangular outlines formed of horizontal and vertical lines at the lower part of the secretary constitute the drawers A, the panels B, and the rail A'. The rectangular

outlines arranged in a rearwardly and upwardly inclined plane at the middle part of 30 the secretary constitute the desk-top C, which is hinged at its lower part and which opens downward, so as to rest on the rail A'.

D are the vertical pillars at the front and upper part of the secretary, and the horizontal outlines at this part constitute the shelves 35 E and drawers F.

G and G' show the radiating fan-shaped ornamentation at the middle of the upper part of the secretary and on its sides. The ornamentation G is in four similar portions behind the plane of the pillars and about the sides of a square panel g, having its said sides inclined at angles of forty-five degrees. The ornamentation G' is on the sides of the secretary at the ends of the desk-top.

What I claim is—

The design for a secretary as herein described and shown.

In testimony whereof I affix my signature 50 in presence of two witnesses.

ALBERT W. GRUNWALDT.
